UNITED STATES PATENT OFFICE

AUGUST PFINGSTEN, OF ROCK RAPIDS, IOWA

BREAD BOX

Application filed January 15, 1931. Serial No. 509,005.

This invention relates to a bread box, the general object of the invention being to provide means whereby slices of bread can be cut from the loaf without removing the loaf 5 from the box, with means whereby slices of even thickness can be cut.

Another object of the invention is to provide an extension on the box for receiving the slices as they are cut from the loaf and 10 to provide a cover for the extension for protecting the same from dirt and dust when the box is closed.

This invention also consists in certain other features of construction and in the combination and arrangement of the several parts, 15 to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:

Figure 1 is an elevation of the improved 25 box.

Figure 2 is a top plan view.

Figure 3 is a detail sectional view showing the covers in open position.

Figure 4 is a plan view of Figure 3.

As shown in these views, the numeral 1 30 indicates the bread box and 2 the cover thereon. One end of the box is formed with an opening 3 and a vertically arranged slit or slot 4 is formed in one side of the box, preferably the front side, a slight distance from the end which has the box opening 3 therein. A flange 5, extends outwardly from the side of the box to surround the slit or slot 4.

An extension 6 is formed on the bottom of the open end of the box and this extension slopes upwardly from said bottom and end pieces 7 of substantially triangular shape have their large ends connected with the ends of the extension and their sides with the sides of the box with their pointed ends merging into the end wall of the box adjacent the top thereof. A cover 8 is hingedly connected with the outer edge of the extension 6 as shown at 9, this cover consisting of a cover-

ing part and side parts, the side parts overlapping the ends 7 of the extension when the cover 8 is raised and the outer edge of the cover part of the cover is so shaped that it will extend under part of the main cover 2 55 of the box when the cover 8 is raised so that the cover 2 will hold the cover 8 in closing position as shown in Figures 1 and 2.

A flexible member 10 connects one end 7 with the cover 8 to limit the downward 60 swinging movement of the cover 8 and handles 11 are attached to the outer face of the cover 8 for facilitating its being moved to open and closed position. These handles rest on the surface on which the box is placed 65 when the cover 8 is open as shown in Figure 3.

A strip 12 preferably of zinc or other soft material placed on the bottom of the box extends through the opening 3 and this strip is 70 formed with a groove 13 which alines with the slit or slot 4 and is adapted to receive the cutting edge of the knife placed in the slit 4 to permit the cutting edge of the knife to pass 75 entirely through the loaf and entirely sever the slice from the loaf.

From the foregoing it will be seen that by opening the covers and moving the loaf in the box to a position where one end is in alignment with the walls of the opening 3 and then pass a knife through the slit 4 and move the knife downwardly through the slit a slice of bread will be cut from the loaf. The slice will drop upon the extension 6 and the cover 8 so that it can be readily picked up and by alining the end of the loaf with the walls of the opening 3 slices of the same thickness can be cut each time the knife is drawn through the loaf. The flange 5 prevents the knife from having sidewise movement and acts as a guide for holding the blade of the knife in a straight position. The knife should be just long enough so that it does not touch the opposite side of the bread box. 85

It is thought from the foregoing description that the advantages and novel features of the invention will be readily apparent.

It is to be understood that changes may be made in the construction and in the combina- 100

tion and arrangement of the several parts, provided that such changes fall within the scope of the appended claim.

Having thus described my invention, what

5 I claim as new is:

5 A bread box comprising a container and a cover therefor, an opening in one end of the container and one side wall of the container having a vertically arranged slit therein located adjacent the open end of the box whereby a knife can be passed through the slit and drawn through a loaf of bread to cut a slice therefrom, and an outwardly extending flange surrounding the slit and forming guiding means for the knife, an extension at the open end of the container comprising a bottom part and a pair of side parts, the outer edges of said side parts sloping upwardly and inwardly to the top of the box and a cover 20 part hinged to the outer part of the bottom part of the extension for covering the same and the open end of the box when said cover part is in raised position.

25 In testimony whereof I affix my signature.

AUGUST PFINGSTEN.
